FOLDING BOX

Hans Pabst, Leipzig, Germany

Application March 19, 1938, Serial No. 196,944
In Germany July 15, 1937

1 Claim. (Cl. 229—23)

Round boxes have been known for a long time. They are supplied by the manufacturing industries gummed or pressed complete. On account of the manufacturing costs and shipping expenses being considerably elevated, these beautiful boxes were not so successful as the straight edge folding boxes.

Experiments of various kinds have been made to manufacture collapsible round boxes, which failed however, as the mounting of the boxes required too much work and involved greater consumption of materials, and for many other difficulties.

It is known to make a collapsible roller-like cardboard box, in which the openings of the closed cardboard roller are closed with cap-like covers.

It is also known to make a non-gummed cardboard box in such a manner that by the aid of die moulds the individual parts are lined with thin paper and thereby kept together.

The two mentioned boxes are of a somewhat similar type, but as regards the principles and construction, they deviate so greatly from the present invention that a comparison with the latter turns out very unfavourably for them.

Special features of the present invention are: (A) Low manufacturing cost; (B) saving in materials; (C) allows great variety of box forms without particular difficulties in the manufacture or construction; (D) individual parts can be packed and stored in flattened out position, thereby saving space; (E) all parts have smooth surfaces allowing text or ornaments to be printed on; (F) simple mounting of the box by jointing, without further operations such as gumming, stitching and without the use of machines, tools, etc.

Fig. 1 shows the bottom of the box formed by the two disks 1 and 2. The dotted line 3 represents the outside gumming line.

Fig. 2 shows the cross-section of the bottom and in which way the two disks are pasted. In particular here the ungummed rim and the slot-like groove become visible.

Fig. 3 shows the rim of the bottom part of the box. The flaps 4 and 5 which are bent rectangularly inwardly at the score lines 6 in setting the box together. The flaps 5 only serve for decorative purposes. The closing of the rim consists of slot 7 and the flap 8.

Fig. 4 shows the lid of the box which only distinguishes itself from Fig. 1 by a somewhat larger diameter.

Fig. 5 shows the rim of the lid which only distinguishes itself from Fig. 3 by an extended length according to Fig. 4.

Fig. 6 shows the set up bottom part of the box.

Fig. 7 shows the set up upper part of the box.

In order to describe the invention more clearly, reference is made to the annexed drawing showing a box of circular shape with loose cover as in Figs. 6 and 7, in which

No. 1 is a plate forming the base part, to which a smaller plate 2 is gummed, stitched or attached in any other way in such a manner that the gummed surface, or fastening line begins at or on line 3 (Figs. 1 and 2) in inward direction. Thereby, a free, slot-like grooved rim 2—3 is formed which is designed to receive the teeth of the belt. The exact length of the belt part is determined by the circumference of plate 2. The lengthwise sides of the belt (Fig. 3) of the base part are provided with round teeth 4, 5 which serve, partly for jointing the double bottom, partly for stiffening and decorative purposes (as visible, see Fig. 6). The score lines 6, 11 enable the teeth to be folded over easily and precisely.

The parts of the top (Figs. 4 and 5) are distinguished from those of the bottom part only in two respects: the belt of the upper part and therefore also plate 9 must be of longer or larger form as they will later have to fit over the belt of the bottom part. The belt of the top part is provided with teeth only on one side, Fig. 5.

When mounting the box, the teeth of the belt are bent rectangularly in inward direction and set into the groove of the corresponding plates of the upper or lower part, respectively. When closing the lock 8, by inserting it into the slot 7, the teeth are forced firmly into the grooved rim, holding the box parts together in a useful manner. The lock can also be of any other suitable design. Figs. 6 and 7 show the round folding box mounted complete in opened condition.

By giving the double plates different forms it is possible to produce a great variety of box shapes.

The invention cannot only be used in connection with thick paper and cardboard, but is also suitable for metallic and modern raw materials.

Having now described my invention I declare that I claim as new:

A round folding box consisting of bottom, cover, and two flattened out rims which, when required, can be set up by the user to form a two-part box without glue or other additional means thus characterized that the bottom and cover consist of two cardboard disks which are glued together in such a way that the rims are lying unglued on top of each other in a certain depth forming a slot-like groove in which rectangularly bent rim-flaps are inserted and, in closing the rims, connect the bottom and the cover respectively firmly with the rims.

HANS PABST.
